CLAIM

The ornamental design for electric mosquito swatter, as shown and described.

DESCRIPTION

FIG. 1 is a front perspective view of electric mosquito swatter, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detail view of area 9 in FIG. 1.

The broken lines in the drawings illustrate the portions of the electric mosquito swatter which form no part of the claimed design.

The long-dash/short-dash broken lines in FIGS. 1 & 9 depict the extent of the enlarged view that form no part of the claim.

1 Claim, 9 Drawing Sheets
